INVENTOR

BY *Nietor J. Evans*

ATTORNEY

WITNESS:

UNITED STATES PATENT OFFICE.

JOHN T. TURNER, OF EXMORE, VIRGINIA.

PROTECTOR.

Application filed May 26, 1926. Serial No. 111,790.

This invention relates to an attachment for the hood of a motor vehicle, the general object of the invention being to provide means for preventing the water which drips through the hinge of the hood from reaching the spark plugs and wires of the motor.

This invention also consists in certain other features of construction and in the combination and arrangement of the several parts, to 10 be hereinafter fully described, illustrated in the accompanying drawings and specifically pointed out in the appended claims.

In describing my invention in detail, reference will be had to the accompanying drawings 15 wherein like characters denote like or corresponding parts throughout the several views, and in which:—

Figure 1 is a sectional view through the hood and adjacent parts of a motor vehicle, 20 showing the invention in use.

Figure 2 is a section on line 2—2 of Figure 3.

Figure 3 is a section on line 3—3 of Figure 2.

Figure 4 is a perspective view of one of the hooks.

Figure 5 is a transverse sectional view showing a modification.

As is well known, the water dripping through the hinge of a hood of a motor vehicle often short circuits the ignition system by dropping on the spark plugs and wires of the motor. I prevent this water from reaching the spark plugs and wires by placing a trough-like member under the hinge of the hood so as to drain the water to a point beyond the front end of the motor. Figures 1, 2 and 3 show a trough-shaped plate 1 placed under the hinge of the hood and having a tubular part 3 at each edge thereof. Each tubular part contains a coiled spring 4 which has its ends connected with the hooks 5, the hooks extending from the tubular part and being adapted to engage the ends of the hood, as shown at 6 in Figure 2. I prefer to form these hooks of wire,

as shown in Figure 4, with the hook at one end and an eye at the other, the eye receiving the end of the spring. I also prefer to cover the springs with waterproof fabric. 50

Figure 5 shows a slight modification in which the trough-shaped plate 1' has an extension 7 at one side thereof which is fastened to one leaf of the hood by rivets 8.

In both forms of the invention, it will be 55 seen that the water dripping through the hinge will be caught by the trough and directed to a point beyond the front end of the engine so that this water will be prevented from dropping upon the spark plugs 60 or wires of the motor.

I prefer to make the device shown in Figures 1, 2 and 3 of flexible waterproof material, such as canvas, though, of course, it could be formed of other flexible material. The hook 5 can also be made of flat thin steel. In the form shown in Figure 5, I prefer to place a strip 7' of rubber or the like between the trough-shaped member and the hood to prevent leakage and vibration. 70

It is thought from the foregoing description that the advantages and novel features of my invention will be readily apparent.

I desire it to be understood that I may make changes in the construction and in the 75 combination and arrangement of the several parts, provided that such changes fall within the scope of the appended claim.

What I claim is:—

In combination with the hood of a motor vehicle, a trough-shaped member placed under the hinge part of the hood for receiving water dripping through the hinge, said member having a tubular part at each side edge thereof, a coiled spring in each tubular part and a hook at each end of each spring, said hooks projecting from the ends of the tubular parts and engaging end portions of the hood to hold the device on the hood.

In testimony whereof I affix my signature.

JOHN T. TURNER.
